CONTAINERS FOR CANS

John A. Kilmartin, Yonkers, N.Y.

Application March 18, 1950, Serial No. 150,416

23 Claims. (Cl. 220—115)

This invention relates to a novel portable carrier or pack for a plurality of cans and means of loading it. More particularly this invention is designed to provide a portable can carrier which also acts as a can display.

A great number of portable carriers for bottles are known. For the most part these bottle carriers are characterized by the desirable property of displaying the label of the bottled merchandise. This is a highly desirable feature in view of the huge sums expended by bottlers in establishing a distinctive bottle. The novel portable can carrier or pack of this invention has the desirable feature of displaying the distinctive can label in addition to being readily loaded by machine.

The portable can carrier or pack of this invention is made from a single blank. Solid sections constituting a part of the top and bottom of said carrier in loaded position are connected to one another by a plurality of panels and struts. Advantageously, the carrier contains a carrying handle which is simply formed from the top section; a crease is placed in the top section and the handle is formed by bending a portion of the top section at right angles. The plurality of panels and struts which connect the top and bottom sections are in hinged relationship thereto; the struts are medially positioned between two panels. Each panel consists of a strip and hinged flaps attached to said strips in hinged relationship; these flaps can be bent from the plane of the strips along the hinges and are designed to "hug" a can in the carrier. The panels and struts are creased laterally at positions defining the top and bottom rims of the can to be inserted in the carrier. The portions of the panels located between said top- and bottom-defining creases and the hinges connecting the panels with the top and bottom sections of the carrier form part of the top and bottom of the carrier in loaded position. In the panels the strips gradually widen and the flaps diminish in width a corresponding amount in the portions of the panels forming part of the top and bottom of the carrier in loaded position. Each can receptacle is defined by two panels and a strut; the panels engage the sides of the can and the strut engages the back of the can and prevents rearward motion of the can.

The portable carriers of this invention are loaded by bending each can receptacle and inserting a can into the receptacle while the panels are spread by the circular distortion of the carrier. When the carrier reverts to planar position, each can is snugly held by two panels and a strut. The strips confine the outer portion of the can while the flaps snugly hug the side of the can; a strut confines the can in the proper position by acting as a support for the back of the can. Advantageously, a carrier unit in unassembled position is passed along a belt and formed. As each successive can receptacle, that is, the space defined by two panels and a strut is bent out of planar position, a can is inserted therein. A clearer picture of the novel manner of loading the carrier or pack of this invention will be apparent from the detailed

2

description and drawings which will be presented hereafter.

The carrier is characterized by a plurality of advantages which make it outstandingly superior to available portable can carriers. The carriers of this invention possess 5 merchandising attractiveness, structural strength and compactness in addition to their ready adaptability to machine loading and economic preparation from one strip of box board.

Since the carrier of this invention displays the labels 10 of the cans, as has been indicated previously, it is an aid to merchandizing. The color scheme of the carrier can be blended with the distinctive color scheme of the canned merchandise so that the combination of carrier and displayed can is a very effective sales promoter.

15 The carrier or pack makes a compact unit so that a plurality of units may be loaded into packing cases for transportation of wholesale lots. This feature of the container permits simple delivery of multiple units from the packaging house to wholesale distributor and then to the retainer.

20 Another outstanding feature of the novel can carrier is that its structure allows the use of lighter paper in its manufacture. The outstanding structural strength of this carrier derives from the fact that shock is absorbed by 25 contiguous cans rather than by the carton or a portion thereof.

25 The major advantage of the carrier or pack of this invention is its adaptability to machine loading. Time consuming and expensive hand loading is antiquated by the 30 use of this carrier. Cans are inserted in the carrier as it passes along a belt; as each opening, which is framed by two panels and a strut, is distorted out of a straight plane, a can is inserted therein. When the carrier reasumes a planar position, the inserted cans are tightly and 35 securely positioned in the carrier; each can is bound on either side by the strip portions of adjacent panels; the flaps of adjacent panels snugly embrace side surfaces of the can and a strut outlines the back of the can thereby preventing movement away from the supporting strips 40 and flaps.

40 A further advantage of the novel carrier of this invention is that it can be constructed of less paper than previously known carriers. Because of the inherent 45 strength of the carrier, it can be made from light weight box board. In addition, a carrier can be prepared from a single strip of box board by relatively few operations which comprise merely printing, cutting and creasing. The simplicity of preparation of this carrier will be apparent when the accompanying drawings are discussed in 50 detail.

55 This invention characterized by its novel mode of machine loading and its feature of displaying the canned merchandise can be used either in the form of carriers which possess handles or in the form of packs which do not possess a handle. Beer and canned juices are particularly suited for packing in carriers. A preferred carrier is of the "suitcase" type wherein the cans are introduced into the carrier in open position in double rows and is then folded like a suitcase to form a double row 60 of cans whose backs are adjacent to one another. Other canned goods, such as frozen fruit concentrates, are particularly adaptable to merchandizing in handle-less packs containing two or more cans. In the packs a row of cans is backed by a solid section of box board rather than 65 by an identical assembly of cans.

70 In the accompanying drawings there are shown various views of the novel can carrier. These drawings will visibly demonstrate the superior features of the carrier of this invention. Figure 1 is a planar view of the preferred "suitcase" type carrier as it appears in unassembled position prior to loading; Figure 2 is a perspective of an

unloaded carrier which has been folded into its normal configuration; Figure 3 is a side elevation of the carrier loaded with cans. Figure 4 is an end elevation of the loaded carrier along the plane 4—4' of Figure 3; Figure 5 demonstrates how the carrier is loaded by angular distortion of the carrier resulting in spreading of the cans engaging panels.

Figure 1 is a view of an unassembled "suitcase" carrier. The two portions of the carrying handle are designated by 1 and 1'. The top, 2 and 2', of the carrier comprises a solid top section 3 and 3' and the parts of the panels and struts of the carrier falling between the hinges 4 and 4' and the creases 5, 5'. The sides 7 and 7' of the carrier comprise those portions of the panels and struts falling between the top defining creases 5, 5' and the bottom defining creases 6, 6'. The bottom 10 of the carrier comprises the bottom section 11 and the portions of the panels and struts falling between the bottom defining creases 6, 6' and the hinges 12, 12'. The panels 14, 14' comprise flaps 15, 15' and strips 16, 16'. The dotted lines 17, 17' designate the creases which connect the strips and flaps in hinged relationship. The struts 20, 20' act as a support for the back portion of the can. The solid lines 21, 21' designate the cuts by which the struts 20, 20' are separated from the panels 14, 14'.

It is apparent from an inspection of Figure 1 that the carrier of this invention can be manufactured from a single strip of box board. The only operations involved in its manufacture from a single strip are printing, cutting and creasing.

Figure 1 is also representative of the open position in which the carrier is loaded. The carrier in open planar position is formed by hand or machine into a unit having a can receptacle and passes along a belt; as the carrier is distorted from the planar position two cans are fed into the two horizontal receptacles passing through the area of maximum distortion; thus the carrier is loaded two cans at a time until the unit is filled. When the unit is filled, the open carrier is folded like a suitcase along hinges 12, 12' adjacent to bottom section 11 of the carrier. The carrier can be locked in assembled position by staples or other conventional means locking together handle sections 1 and 1'.

Figure 2 is a perspective of an empty carrier which has been folded into the configuration it possesses when loaded. It is apparent from Figure 2 how the struts 20, 20' confine the cans and prevent backward motion thereof. It is also apparent how the strips 16, 16' and flaps 15, 15' snugly contain the sides of each can. It is further apparent from Figure 2 how the top of the carrier in assembled position comprises top sections 3, 3' and portions of the panels and struts falling between the hinges 4, 4' and the creases 5 and 5'. The bottom of the carrier 10 comprises solid bottom section 11 and the portions of the panel and struts falling between the bottom-defining crease 6, 6' and the hinges 12, 12'.

Figure 3 is a side elevation of the loaded carrier. The cans 30 are clearly visible outlined by the strips 16. It is apparent from Figure 3 that the close juxtaposition of the cans absorbs the shocks which the carrier is subjected to in normal usage. Figure 3 also illustrates the value of the carrier of this invention as a merchandizing aid. It is apparent that a distinctive can marking is clearly visible.

Figure 4 is an end elevation of the loaded carrier along the axis 4—4' of Figure 3. It is clearly apparent from this figure how the struts 20, 20' confine the cans 30 in their designated place in the carrier. Moreover, it is apparent there is no undue strain on struts 20, 20' because of the close, substantially contiguous position of the cans. The major portion of any shock is not taken by the struts but by the cans which they confine.

Figure 5 shows how the carrier of this invention is simply loaded. Angular distortion of the carrier from planar position results in separation of the panels 14 comprising strips 16 and flaps 15. In the drawing the major

amount of angular distortion is realized at the points 28 on the top and bottom of the carrier on the top hinge 4 and bottom hinge 12. The can 30 is inserted in the opening between the panels 16 while the carrier is in the spread position. As the carrier reassumes its normal plane of position, the can 30 is confined in its receptacle between strut 20 and between flaps 15 and strips 16 of each panel. It is apparent from this figure that the carrier can be readily loaded by machine.

Although the carrier of this invention has been illustrated with conventional flat top cans, it can also be employed for cone-top cans. All that is required to adapt the carrier to cone-top cans is a slight rearrangement in the positioning of the creases at the top of the cans. The creases in the struts are placed higher than the creases in the accompanying panels to adapt the carrier to cone-top cans. Thus referring to Figure 1 the carrier is adapted to the use of cone-top cans by staggering the creases 5 and 5'; the creases 5, 5' are made higher on the struts 20, 20' than on the strips 16, 16' and flaps 15, 15' of the panels 14, 14'.

The invention has been described as adapted for a unit of six cans. It is apparent that the carrier is adaptable to use of either more or fewer cans per unit.

The description of the can container of this invention has been entirely devoted to "suitcase" carrier. It is reiterated that the invention is equally as well suited for handle-less packs. A pack would utilize but half the unit shown in the aforesaid diagrams; the row of cans which 30 serves as a backing in the described "suitcase" carrier would be supplanted by a solid section of box board. In addition, the pack does not contain a handle.

The pack-type carrier is illustrated in Figures 6 and 7. Figure 6 is a view of an unassembled pack type carrier 35 while Figure 7 is a perspective of an empty pack-type carrier. In both these figures the top 35 of the carrier comprises a solid top section 36 and parts of the panels 45 and struts 50 of the carrier falling between the hinge 37 and the crease 38. The bottom 39 of the carrier comprises a bottom section 40 and the portions of the panels 45 and struts 50 falling between the bottom-defining crease 42 and the hinge 41. The panels 45 comprise strips 46 and flaps 47. The crease lines 53 connect the strips 46 and the flaps 47 in hinged relationship. The struts 50 are separated from the panels 45 by the cut score lines 52. The back 55 of the pack-type carrier is connected to the bottom of the carrier 39 by the crease line 57. There is attached to the back 55 a glueing tab 56.

It is apparent that the novel carrier of this invention can be used with other cylindrical containers as well as with cans. For example, the carrier of this invention serves well in the packing of two or more glass jars.

Obviously many modifications and variations of the invention, as hereinbefore set forth, may be made without departing from the spirit and scope thereof, and therefore only such limitations should be imposed as are indicated in the appended claims.

I claim:

1. A portable can carrier adapted for machine loading comprising top and bottom sections, a plurality of panels consisting of strips and hinged flaps, struts medially positioned between said panels, said top and bottom sections being connected by said panels and said struts, both said panels and struts being in hinged relationship with said top and bottom sections, each can receptacle being defined by a strut and two adjacent panels, said panels forming the side walls of said carrier and said struts serving as retainers for the back of cans inserted therein, both said panels and struts being provided with lateral creases at positions defining the lower and upper rims of said cans, and portions of said panels and struts above and below said creases forming part of top and bottom of said carrier.

2. A carrier of the type described in claim 1 in which the top section terminates in a carrying handle.

3. A carrier of the type described in claim 1 in which the can receptacles are lined up in two horizontal rows so that each row of cans in the container is backed by an identical assembly of cans.

4. A portable can carrier adapted for machine loading comprising a back consisting of a solid section, top and bottom sections, a front section comprising a plurality of panels consisting of struts and hinged flaps and struts medially positioned between said panels, said top and bottom sections being connected by said panels and struts, both said panels and struts being in hinged relationship with said top and bottom sections, each can receptacle being defined by a strut and two adjacent panels, said panels forming the side walls of said carrier and said struts serving as retainers for the back of cans inserted therein, both said panels and struts being provided with lateral creases at positions defining the lower and upper rims of said cans, and portions of said panels and struts above and below said creases forming part of top and bottom of said carrier.

5. A process for exterior loading a can carrier adapted to hold multiple can units and containing a plurality of can receptacles defined by rear struts retaining the back of said cans and by front panels retaining the sides of said cans which comprises forming said carrier so that each can receptacle is outlined, bending said carrier about a pivot intermediate said rear struts and front panels out of planar position so that the side-retaining panels of said receptacles are distended, inserting cans into said receptacles while in said distended position and restoring said carrier to a planar position whereby each can is successively retained in its receptacle by the action of the defining struts and panels.

6. A process according to claim 5 in which an adjacent pair of receptacles are distended and cans are inserted into said receptacles in pairs.

7. A process according to claim 5 in which successive portions of said formed carrier are continuously bent out of planar position and said can receptacles are continuously and successively distended for insertion of cans therein.

8. A container carton having individual pockets for containers and comprising a base member and a pair of top members, strut and panel elements connected with the base member and the respective top members along corresponding lines and provided with generally upright portions alternately offset inwardly and outwardly of said lines and having connecting portions extending respectively inwardly and outwardly from the tops and bottoms of the upright portions to connect with said members, each of said inwardly offset upright element portions cooperating with two outwardly offset upright element portions to provide a container-confining cage.

9. The device of claim 8 in which the connecting portions extending outwardly have convergent side flanges and the outwardly offset upright panel elements have integral side flanges extending convergently inward and connected with the side flanges first mentioned to lie in substantially flat engagement with a confined container.

10. A carton blank comprising sheet material having integral strut and panel elements of less length than the blank and defined along their side margins by longitudinal cut score lines and at the end of said elements by first crease score lines transverse to and intersecting said cut score lines, said blank being provided with second transverse crease score lines continuous through said strut and panel elements and equally offset toward each other from said first transverse crease score lines, whereby in the course of carton erection alternate portions of said strut and panel elements of the blank at opposite sides of a cut score line may be equally offset into parallel planes at opposite sides of the plane originally occupied by the blank, said plane constituting a plane common to said first transverse crease score lines.

11. A carton blank comprising sheet material having

integral strut and panel elements of less length than the blank and defined by longitudinal cut score lines and by first crease score lines transverse to and intersecting said cut score lines and by second transverse crease score lines offset toward each other from said first transverse crease score lines, whereby in the course of carton erection alternate elements of the blank at opposite sides of a cut score line may be equally offset into planes at opposite sides of the plane originally occupied by the blank, said elements being further provided between alternate pairs of longitudinal cut score lines with paired longitudinal crease score lines parallel to said cut score lines and extending between said second transverse score lines whereby the portions of each element between said crease lines and 15 cut lines may be hingedly moved on said last crease line into planes oblique respecting the portion of the blank between said crease lines.

12. The carton blank of claim 11 further provided with oblique crease score lines extending from the junction of said crease score lines with said second transverse crease score line to the junction of said cut score line with said first transverse crease line whereby the portion of the blank bounded by said oblique crease score lines, said cut score lines and said second transverse crease line 25 may be folded back on said oblique crease score line into face relation with the remaining portions of the blank between said first and second transverse crease score lines.

13. A carton blank comprising sheet material having end portions comprising handles of the carton when erected and a center portion comprising the bottom of the carton when erected, longitudinal cut score lines extending between said end portions and said center portion and terminating at said portions to define strut and panel elements, first crease score lines transverse to said cut score lines and intersecting the ends of said cut score lines in said end and center portions, second transverse crease score lines continuous through said strut and panel elements and equally offset toward each other from said first transverse crease score lines, the extent of said offset being substantially one-half the extent of discontinuity 30 of said cut score lines across said center portion of the blank whereby in the course of carton erection said blank may be hinged on the said first transverse crease score lines in the center portion of the blank to fold the blank into U shape and said elements adjacent to a cut score line may be equally infolded and outfolded into parallel planes at opposite sides of the plane originally occupied by the blank proper, with the infolded portions in substantially face to face relationship throughout their length between said second transverse crease score lines.

14. The process of loading a container carton having front and rear elements forming side opening pockets arranged in end to end relation and having a medial anchorage piece to which said elements are mutually connected intermediate said front and rear elements and comprising flexible joints at said connections, comprising the steps of flexing said joints and said connections intermediate said front and rear elements to widen said side openings, inserting a container in said pocket through said side opening, and restoring the joint to normal unflexed position.

15. A container carton having an individual pocket for a container, said carton comprising at least three container-confining elements mutually spaced at a distance less than the container width, at least two elements being laterally spaced in a common plane, and upper and lower anchorage members with which the elements are all connected at points between the said common plane and the third element, the elements having terminal portions extending forwardly and rearwardly above and below the pocket to said points.

16. The device of claim 15 in which at least two of said elements have integral flanges extending in a direction generally tangent to the wall of the confined container.

17. The device of claim 15 in which said elements and anchorage members are integral and said members are disposed in substantially parallel planes, substantially at right angles to said common plane of the two elements aforesaid.

18. A method of loading containers into a carton comprising two multiple compartment sections connected by an intermediate web and each having mutually spaced front and rear elements forming side opening pockets, the front and rear elements of each section being provided with anchorage pieces intermediate said front and rear elements and to which said elements are mutually connected to constitute said connections as flexible joints, comprising the steps of substantially aligning the sections oppositely of the web so that the respective sections are free for flexing on said joints, and flexing corresponding joints of each said section simultaneously to widen the pocket opening of corresponding pockets in said sections, inserting containers into the pockets of each said section thus widened, and restoring the flexed joints to normal unflexed position.

19. The method of claim 18 plus the final step of pivoting said sections on said intermediate web to dispose the rear elements in said sections in back to back relationship whereby said container pockets are aligned in adjacent rows for carrying purposes.

20. A carton comprising interconnected parts including a top, a bottom, rear wall panels and front wall panels, said rear and front wall panels being staggered in mutually offset planes, said top, bottom and front wall panels being provided with inturned interconnected flaps, said top and bottom flaps being transverse to said front wall panel flaps to constitute braces to support said front panel flaps at a substantially fixed oblique angle to said front panels to coact with said rear wall panels in defining container pockets.

21. A can package including a bottom panel, side wall panels foldably connected along opposite edges of said bottom panel, and a top panel connecting the upper edges of said side panels, cans on said bottom panel between said side wall panels, each side panel including therein a series of spaced apertures extending from top to bottom

5

thereof, said apertures being substantially narrower than the diameter of said cans and having substantially parallel side edges, and inwardly extending flanges foldably connected to said side edges and held in diverging relation by the cans contained.

22. The construction described in claim 21 and including a pair of handle flaps extending upwardly from said top panel intermediate of, and foldably connected with, said top panels.

23. A container carton comprising a front and a rear wall, said front wall comprising panels spaced to define an opening and a loading pocket behind said opening through which containers are loaded, said opening being of less width than a container to be loaded into the pocket through said opening, said front wall panels having connections between panels comprising relatively flexible hinge portions laterally offset from said panels and on which said panels are swingable to permit widening of the spacing between panels to admit a container to the pocket, said rear wall having hinged portions, together with a top element with which the hinge portions of said front and rear walls have a common line of connection, the front and rear walls being offset respectively to the front and rear of a plane common to said line.
